(57) **CLAIM**

The ornamental design for a tool rack apparatus, as shown and described.

DESCRIPTION

FIG. 1 illustrates a perspective view of a tool rack apparatus showing my new design.

FIG. 2 is a front elevational view of the apparatus of my new design shown in FIG. 1.

FIG. 3 is a rear elevational view of the apparatus of my new design.

FIG. 4 is a left side elevational view of the apparatus of my new design.

FIG. 5 is a right side elevational view of the apparatus of my new design.

FIG. 6 is a top plan view of the apparatus of my new design.

FIG. 7 is a bottom plan view of the apparatus of my new design.

FIG. 8 is a perspective view of the tool rack apparatus showing my new design, wherein the broken line showings of the tool racks are for illustrative purposes only and form no part of the claimed design; and,

FIG. 9 is a perspective view of the tool rack apparatus similar to FIG. 8, but showing the support arms in alternate positions, wherein the broken line showings of the tool racks are for illustrative purposes only and form no part of the claimed design.
